Primary Examiner — Darlington Ly(74) *Attorney, Agent, or Firm* — Kelly & Kelley, LLP(57) **CLAIM**

The ornamental design for a pipe chuck teeth, as shown and described.

DESCRIPTION

FIG. 1 is a front, top, and right side perspective view of the pipe chuck teeth;

FIG. 2 is a rear, top, and left side perspective view of the pipe chuck teeth;

FIG. 3 is a left side view of the pipe chuck teeth;

FIG. 4 is a right side view of the pipe chuck teeth;

FIG. 5 is a top view of the pipe chuck teeth;

FIG. 6 is a bottom view of the pipe chuck teeth;

FIG. 7 is a front view of the pipe chuck teeth; and,

FIG. 8 is a rear view of the pipe chuck teeth.

The broken lines in the drawings illustrate features of the pipe chuck teeth and environmental structure of a pipe chuck that forms no part of the claimed design.

1 Claim, 8 Drawing Sheets---
